COMBINED URINAL HOLDER AND DEODORANT CAP

Blanton D. Love, Houston, Tex., assignor to Hazel H. Crosby, Houston, Tex.

Application December 24, 1952, Serial No. 22,865

Term of patent 14 years

(Cl. D83—1)

To all whom it may concern:

Be it known that I, Blanton D. Love, a citizen of the United States, residing at Houston, in the county of Harris, State of Texas, have invented a new, original, and ornamental Design for a Combined Urinal Holder and Deodorant Cap, of which the following is a specification, reference being had to the accompanying drawings, forming a part hereof.

Fig. 1 is a side view of a combined urinal holder and deodorant cap embodying my new design, the urinal being shown in dashed outline for purpose of illustration;

Fig. 2 is a side view taken at right angles to and looking to the right of the view of Fig. 1;

Fig. 3 is a side view taken from the opposite side of the combined holder and cap as shown in Fig. 1; and

Fig. 4 is a top plan view of the design illustrated in Fig. 2.

What is claimed is:

The ornamental design for a combined urinal holder and deodorant cap, substantially as shown and described.

BLANTON D. LOVE.
